UNITED STATES PATENT OFFICE

121,112

DESIGN FOR A SHOE RACK

Bruno Deja, Brooklyn, N. Y.

Application April 17, 1940, Serial No. 91,734

Term of patent 7 years

To all whom it may concern:

Be it known that I, Bruno Deja, a citizen of the United States, residing at Brooklyn, in the county of Kings and State of New York, have invented a new, original, and ornamental Design for a Shoe Rack, of which the following is a specification, reference being had to the accompanying drawing, forming part thereof,

The figure is a perspective view of a shoe rack, showing my new design.

I claim:

The ornamental design for a shoe rack, as shown.

BRUNO DEJA.
